US00D859800S

(12) **United States Design Patent** (10) Patent No.: **US D859,800 S**
(45) Date of Patent: ** Sep. 17, 2019

(54) **SOLE**

(71) Applicant: **Reebok International Limited**, London (GB)

(72) Inventors: **William Marvin**, Canton, MA (US); **Matthew Montross**, Middleboro, MA (US)

(73) Assignee: **Reebok International Limited**, London (GB)

(**) Term: **15 Years**

(21) Appl. No.: **29/645,899**

(22) Filed: **Apr. 30, 2018**

Related U.S. Application Data

(60) Continuation of application No. 29/603,895, filed on May 12, 2017, now Pat. No. Des. 818,683, which is (Continued)

(51) **LOC (12) Cl.** **02-04**

(57) **CLAIM**

The ornamental design for a sole, as shown and described.

DESCRIPTION

FIG. 1 is a bottom plan view of a sole showing the claimed design;

FIG. 2 is a side view thereof; and,

FIG. 3 is another side view thereof.

The dashed broken lines in the figures show portions of the sole and environment that form no part of the claimed design. The dot-dashed broken lines in the figures show boundaries that form no part of the claimed design.

1 Claim, 3 Drawing Sheets

Related U.S. Application Data

a continuation of application No. 29/549,289, filed on Dec. 21, 2015, now Pat. No. Des. 786,544, which is a division of application No. 29/470,409, filed on Oct. 21, 2013, now Pat. No. Des. 746,032, which is a division of application No. 29/443,382, filed on Jan. 16, 2013, now Pat. No. Des. 693,552, which is a division of application No. 29/378,310, filed on Nov. 2, 2010, now Pat. No. Des. 675,002.
